Isaac H. Hobbs

UNITED STATES PATENT OFFICE.

ISAAC H. HOBBS, OF PHILADELPHIA, PENNSYLVANIA.

IMPROVED APPARATUS FOR SEPARATING AND COLLECTING GAS FROM PETROLEUM.

Specification forming part of Letters Patent No. 44,421, dated September 27, 1864.

To all whom it may concern:

Be it known that I, ISAAC H. HOBBS, of the city of Philadelphia, in the State of Pennsylvania, have invented a new and useful improvement in the apparatus for restoring the production of oil-wells that have ceased to flow, and for separating and preserving the gas thereof for use; and I do hereby declare that the following is a full, clear, and exact description of the construction and operation of the same, reference being had to the accompanying drawing, and to the letters of reference marked thereon.

The nature of my invention consists, substantially, as hereinafter described and specified, in the employment of any suitable lift and force pump between and in combination with an exhaust or vacuum vessel communicating with the oil in the well, and a spacious receiver provided with a pipe fixed at its apex and communicating with any suitable gasometer, and with a discharge-pipe for running off the oil into barrels or any suitable holder.

In the drawing, A represents the exhaust or vacuum vessel, and a' the pipe communicating therewith and with the oil of the well; B, the receiver; b', the pipe leading therefrom to the gasometer, (not shown in the drawing,) and b² the discharge-orifice for the oil, and C the lift and force pump, communicating with both vacuum-vessel A and the receiver B.

The exhaust-vessel A is a hollow cylinder, of boiler-iron, and the pipe a' is the upper end of the usual well-pipe, attached to or near the upper side of the vessel A.

The receiver B is also an iron vessel, and has a flat bottom and a dome-top, into which latter one end of the gas-pipe b' opens, while its other end is made to extend to and open into any suitable gasometer. The discharge-orifice b² is intended to be connected with a pipe leading to any suitable oil-holder, and to be fitted with an appropriate stop and flow cock.

The lift and force pump C in the present instance is intended to represent one of that class which is provided with two valved pistons jointed respectively to each end of a le-

ver in the central portion, c', of the pump, the said lever being fixed on a shaft passing through the portion c', and arranged to be operated in an oscillating manner by means of an outside lever, a², connected with the motive power; but as any suitable lift and force pump is intended to be used, the interior construction of the pump C need not be shown in the drawing.

Operation: The lift and force pump being put in operation, a vacuum will be produced in the vessel A, and the pressure of the atmosphere being thus removed, the oil in the well-pipe a' will flow into the said vessel—the head of course being sufficient—from whence it will be drawn and forced by the pump into the receiving vessel B. The stop cock of the pipe attached at b² is now to be closed and kept so until the oil shall reach above the said orifice—say to the dotted line x—when it is reopened sufficiently to keep the inflowing oil always a little above the said outlet b², and consequently the gas will rise from the oil into the dome, and be continually pressed forward through the pipe b' into the gasometer.

It will therefore be readily seen that by means of this apparatus wells that have ceased to flow can again be made productive, (there being of course a sufficient head,) and that the gas will also be separated from the oil, and preserved for use as fuel, light, &c.; besides, the apparatus is simple and inexpensive.

I wish it to be distinctly understood that I do not desire to claim either the exhaust-vessel A, the receiving-vessel B, or the lift and force pump C, individually considered; but,

Having fully described my improved apparatus, what I claim as new therein of my invention, and desire to secure by Letters Patent, is—

The employment of a lift and force pump, C, between the exhaust or vacuum vessel A and the receiver B, the whole being constructed, arranged, and combined to operate together in the manner described, for the purposes specified.

ISAAC H. HOBBS.
